UNITED STATES PATENT OFFICE.

WILMER S. SNOW, OF CHICAGO, ILLINOIS.

DESIGN FOR A LIGHTING-FIXTURE.

49,372.

Specification for Design. Patented July 11, 1916.

Application filed May 22, 1916. Serial No. 99,244. Term of patent 3½ years.

To all whom it may concern:

Be it known that I, WILMER S. SNOW, a citizen of the United States, residing at Chicago, in the county of Cook and State of Illinois, have invented a new, original, and ornamental Design for a Lighting-Fixture, as shown, reference being had to the accompanying drawings, forming a part thereof.

In the drawings, the figure is an elevation of my fixture.

I claim,—

The ornamental design for a lighting fixture as shown.

Signed at Chicago, in the county of Cook, and State of Illinois, this 15th day of May, 1916.

WILMER S. SNOW.

Witnesses:

E. C. MCKINNIE,
J. K. SELLECK.
